ADJUSTABLE CASTER

Filed Jan. 14, 1922

Inventor

J. Carlson

By *Watson E. Coleman*
Attorney

UNITED STATES PATENT OFFICE.

JOHN CARLSON, OF LA TUQUE, QUEBEC, CANADA.

ADJUSTABLE CASTER.

Application filed January 14, 1922. Serial No. 529,235.

To all whom it may concern:

Be it known that I, JOHN CARLSON, a citizen of the United States, residing at La Tuque, in the Province of Quebec, Canada, 5 have invented certain new and useful Improvements in Adjustable Casters, of which the following is a specification, reference being had to the accompanying drawings.

This invention relates to furniture casters, 10 and particularly to adjustable casters whereby the caster may be adjusted relative to the leg of a table, chair or other article to which the caster is applied.

The general object is to provide a caster 15 of this character which is simple in construction, which may be readily adjusted, and which will retain its adjustment.

A further object is to provide a caster of 20 this character in which the adjustment is secured by means of a nut on the caster, which nut is exteriorly disposed so that an implement may be readily applied thereto at any time to rotate the nut and increase or decrease the effective length of the caster.

25 Other objects will appear in the course of the following description.

My invention is illustrated in the accompanying drawings, wherein:—

Figure 1 is a vertical sectional view of a 30 furniture leg and my improved caster applied thereto;

Figure 2 is a fragmentary vertical sectional view taken at right angles to the sectional view shown in Figure 1.

35 Referring to these drawings, it will be seen that my caster consists of practically five pieces. The caster wheel 10 is disposed between the slightly curved and bifurcated end of a shank 11. This shank 11 is tubular and 40 open at its upper end and is exteriorly screw-threaded for a portion of its length, as at 12, these exterior screw-threads being disposed at the beginning of the straight portion of the shank just above the fork within which 45 the wheel 10 is mounted. This shank is transversely slotted, as at 13, the slot being approximately the same length as the screw-threads 12.

50 Disposed within the shank is a pin or spindle 14 which fits the interior of the shank and has sliding engagement therewith, the lower end of this spindle 14 being transversely slotted, as at 15, this transverse recess or groove in the slot being the same size as 55 the slot 13. The upper end of the spindle 14 is provided with a head 16 having an ex-

terior diameter the same as the exterior diameter of the shank 11. The upper face of this head is formed with an upwardly projecting step bearing 17. The shank with 60 its interior spindle is adapted to be disposed within the socket 18, in turn intended to be disposed within the leg of the article of furniture, as illustrated in Figure 1, this socket being closed at its upper end and at its lower 65 end having the outwardly projecting flange 19. The inner face of the closed upper end of the socket is formed with a centrally disposed bearing recess 20 within which the pointed upper end 17 of the spindle 14 bears. 70 Disposed through the slot 13 and the slot 15 is a transversely extending key 21 which may be held from transverse movement through the slot 13 in any desired manner but which has vertical sliding movement in the slot 13, 75 and disposed below the key and engaging this key is a nut 22 engaging the screw-threads 12.

The parts are assembled in the manner shown in Figure 1, and if it be desired to 80 increase the effective length of the leg of the article of furniture to which the caster is applied, the nut 22 is turned upward, causing the key 21 to rise, and this in turn causing the elevation of the spindle 14 relative 85 to the shank 11 to thereby increase the effective length of the shank. The spindle 14 at its upper end bears against the bearing seat 20 and has, of course, free rotation within the socket 18. If it be desired to decrease the 90 effective length of the shank, the nut 22 is turned in the reverse direction, permitting the shank 11 to move upward within the socket and into position against the flange 95 16 on the spindle 14. In order to prevent the detachment of the key 21 after it is put in place, the ends of the key may be slightly overturned or pinned to prevent the key from moving longitudinally through the slot 13. The shank of this caster may be withdrawn from its engagement with the socket at any time, and obviously the spindle 14 may be withdrawn from within the shank 11 if it is desired. The caster may thus be 100 105 withdrawn from its engagement with the socket at any time, and obviously the spindle 14 may be withdrawn from within the shank 11 if it is desired. The caster may thus be readily lubricated, put in position, removed, or replaced.

I claim:—

1. In a caster, a tubular caster wheel supporting shank open at its upper end, a caster wheel, a spindle disposed within the tubular shank and extending above the same, the lower end of the spindle being bifurcated 110

and operatively supporting the caster wheel and the caster wheel and spindle oscillating together, means whereby the spindle may be elevated or lowered relative to the shank and held in its adjusted position, and a socket within which the shank and spindle are disposed, the spindle and socket at their upper ends being formed with complementary bearing portions.

- 10 2. A caster of the character described comprising a caster wheel supporting shank, the shank being tubular and open at its upper end, the lower end of the shank being exteriorly screw-threaded and formed 5 with a transversely extending slot, a spindle disposed within the tubular shank and projecting above the same, a key passing through the slot of the shank and bearing against the lower end of the spindle, a nut 15 engaging the screw-threads of the shank and upon which said key rests, and a socket within which the shank is disposed, the spindle bearing at its upper end against the upper end of the socket.
- 20 3. A caster of the character described comprising a shank forked at its lower end, a caster wheel disposed within the shank, the shank being tubular and open at its upper end, the lower end of the shank above the 25 forked portion being exteriorly screw-threaded and formed with a transversely extending slot having a length equal to the length of the screw-threads, a key extending through said slot, a nut engaging the 30 screw-threads and upon which the key rests, a spindle fitting within the tubular shank and formed at its lower end with a diamet-

rically extending recess to engage said key, the upper end of the spindle having a head, the upper face of the head being formed 40 with an upwardly projecting bearing, and a hollow socket formed at its lower end with an annular flange, the upper end of the socket being closed and having a bearing recess in which the step bearing of the spindle rotatably engages.

4. A caster of the character described comprising a caster wheel supporting shank, the shank being tubular and open at its upper end, the lower end of the shank being exteriorly screw-threaded and formed 50 with a transversely extending slot, a spindle disposed within the tubular shank and extending above the same, a member passing through the slot of the shank and operatively engaged with the spindle, a nut 55 engaging the screw-threads of the shank and upon which said member rests, and a socket within which the shank is disposed, the spindle bearing at its upper end against the upper end of the socket.

5. In a caster, a caster wheel having a shank, a socket within which the shank oscillates, and a nut screw-threaded upon the shank at the lower end thereof and having operative engagement with the socket 65 whereby to cause a retraction of the shank from the socket as the nut is rotated in one direction and permit the movement of the shank into the socket upon a movement of 70 the nut in the opposite direction.

In testimony whereof I hereunto affix my signature.

JOHN CARLSON.
